Primary Examiner — Mehri F Bajoul

(57) **CLAIM**

The ornamental design for a electric vehicle for kids, as shown and described.

DESCRIPTION

FIG. 1 is a front, left and bottom perspective view of a first embodiment of a electric vehicle for kids showing my new design;

FIG. 2 is a rear, right and top perspective view thereof;
FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area **9** in FIG. 1;

FIG. 10 is an enlarged view of area **10** in FIG. 1;

FIG. 11 is an enlarged view of area **11** in FIG. 1;

FIG. 12 is an enlarged view of area **12** in FIG. 1;

FIG. 13 is an enlarged view of area **13** in FIG. 1;

FIG. 14 is an enlarged view of area **14** in FIG. 1;

FIG. 15 is an enlarged view of area **15** in FIG. 2;

FIG. 16 is an enlarged view of area **16** in FIG. 2;

FIG. 17 is an enlarged view of area **17** in FIG. 2;

FIG. 18 is an enlarged view of area **18** in FIG. 2;

FIG. 19 is an enlarged view of area **19** in FIG. 2;

FIG. 20 is an enlarged view of area **20** in FIG. 2;

FIG. 21 is a front, left and bottom perspective view of a second embodiment of a electric vehicle for kids showing my new design;

FIG. 22 is a rear, right and top perspective view thereof;

FIG. 23 is a front view thereof;

FIG. 24 is a rear view thereof;

FIG. 25 is a left side view thereof;

FIG. 26 is a right side view thereof;

FIG. 27 is a top plan view thereof;

FIG. 28 is a bottom plan view thereof;

FIG. 29 is an enlarged view of area **29** in FIG. 21;

FIG. 30 is an enlarged view of area **30** in FIG. 21;

FIG. 31 is an enlarged view of area **31** in FIG. 21;

FIG. 32 is an enlarged view of area **32** in FIG. 21;

FIG. 33 is an enlarged view of area **33** in FIG. 21;

FIG. 34 is an enlarged view of area **34** in FIG. 21;

FIG. 35 is an enlarged view of area **35** in FIG. 22;

FIG. 36 is an enlarged view of area **36** in FIG. 22;

FIG. 37 is an enlarged view of area **37** in FIG. 22;

FIG. 38 is an enlarged view of area **38** in FIG. 22;

FIG. 39 is an enlarged view of area **39** in FIG. 22; and,

FIG. 40 is an enlarged view of area **40** in FIG. 22.

The broken lines in the figures illustrate portions of the

electric vehicle for kids that form no part of the claimed

(Continued)

design. The dot-dash broken lines represent boundaries of the enlarged portions and form no part of the claimed design.
